UNITED STATES PATENT OFFICE.

TAMIS CORNELIS SCHENK, OF DETROIT, MICHIGAN.

APPARATUS ADAPTED FOR CLAMPING TOGETHER TIMBERS, ETC.

Application filed March 30, 1922. Serial No. 548,247.

My invention relates particularly to an apparatus by means of which timbers, poles, etc. may be fastened together in an advantageous manner.

5 The object of my invention is to provide an apparatus by means of which timbers, poles, etc., as, for example, when used in scaffolding for the construction of buildings, may be fastened together without the necessity of cutting them to a particular size and without the waste of labor and materials caused by the use of spikes, nails or screws therein. A further object is to provide a clamping device of this kind which may be 10 manufactured at a minimum cost.

Further objects of my invention will appear in the detailed description hereinafter:

Many embodiments of my invention are possible but I have shown only certain forms 20 thereof in the accompanying drawings in which—

Figure 1 is a side elevation of timbers fastened together in accordance with one form of clamping device made in accordance with 25 my invention and

Fig. 2 is a plan view of the same showing the timbers in cross-section;

Fig. 3 is a side elevation of timbers fastened with another form of locking device 30 embodying my invention;

Fig. 4 is a plan view of the same showing the timbers in cross-section and

Fig. 5 is a plan view of a spanner used with my clamping device.

35 In the drawings, referring first to Figs. 1 and 2, I have shown two timbers 1 and 2 which are overlapped to any desired degree to give the required total length thereof. They are fastened together with clamping

40 devices, each of which is comprised of a U-shaped member 3 made of iron having legs 4. These are bent upwardly at their outer ends to form oblique portions 5, which are provided at their outer ends with bills 6

45 acting as stops for a locking member 7 comprised of a rectangular sheet of iron. As will be seen in Fig. 1, the locking member 7 is first applied in the position shown in the upper portion of said figure and then is 50 turned by a spanner 8 having a handle 9 and a slot 10 fitting over the locking piece so as to rotate the same in the position shown in the lower portion of Fig. 1.

In the modified form of my invention 55 shown in Figs. 3 and 4 there are two timbers 11 and 12 which are overlapped in the

same manner as previously described in connection with the other form of my invention. These timbers are then secured together with clamping devices, each of which comprises a U-shaped member 13 made of iron having legs 14 which are bent laterally near their outer ends so as to produce laterally extended portions 15 providing recesses 16 to receive a rotary locking piece 17 in the form of a flat sheet of iron which is supported at one edge for rotation thereof in hooks 18 carried on the outer ends of the legs 14. The hooks 18, furthermore, have upwardly directed bills 19 which serve as stops 70 in the turning movement of the locking piece 17.

In the utilization of my invention, as exemplified in Figs. 1 and 2, the timbers having been overlapped in the manner described, the 75 U-shaped clamping members are located around the same in the position shown at the upper part of Fig. 1. The upwardly directed portions 5 of the U-shaped member provide ample space for the initial insertion of the 80 locking pieces. The locking pieces 7 are then turned into the position shown in the lower portion of said figure, until they rest against the bills 6, by the application of the spanner 8 which is removed when the locking piece has 85 been rotated into its clamping position, as shown at the bottom portion of Fig. 1.

The form of my invention shown in Figs. 3 and 4 operates in the same manner. In this instance, however, the legs 14 have laterally 90 extending portions to provide space permitting the initial insertion and rotation of the locking piece 17 with the aid of the spanner 8 until they finally rest against the bills 19 as shown in the lower portion of Fig. 3. 95

While I have described my invention above in detail, many changes may be made within the scope of my invention and appended claims.

I claim:

1. A clamping device comprising a U-shaped member provided with legs which are bent to provide laterally extended portions and having hooks terminating in bills at the outer ends thereof, and a locking piece 105 arranged to rotate in said hooks between the lateral bends in the legs and rest in locking position against said bills.

2. A clamping device comprising a U-shaped member provided with legs which 110 are bent to provide laterally extended portions and having hooks terminating in bills

at the outer ends thereof, and a flat locking piece arranged to rotate in said hooks between the lateral bends in the legs and rest in locking position with its side against said bills.

3. A clamping device comprising a U-shaped member having hooks terminating in bills at the outer ends thereof, a wide flat locking piece arranged to rotate in said hooks and rest in locking position against said bills, said bills being of a length substantially equal to the width of said locking piece.

4. The combination with an article to be clamped of a clamping device comprising a

U shaped member having hooks terminating in bills at the outer ends thereof, a locking piece arranged to rotate in said hooks and rest in locking position with its side against said bills and in contact with said article, said bills contacting with the adjacent portion of the locking piece substantially up to the part of the locking piece which contacts with said article.

In testimony that I claim the foregoing, I have hereunto set my hand this 14th day of March, 1922.

TAMIS C. SCHENK.
